V. A. ISAAC

NURSING BOTTLE

Filed March 6, 1923

By *A. Kaufalpky, Jr.*
Attorney

UNITED STATES PATENT OFFICE.

VENIE A. ISAAC, OF WALNUT, IOWA.

NURSING BOTTLE.

Application filed March 6, 1923. Serial No. 623,223.

To all whom it may concern:

Be it known that I, VENIE A. ISAAC, a citizen of the United States, residing at Walnut, in the county of Pottawattamie and 5 State of Iowa, have invented certain new and useful Improvements in Nursing Bottles; and I do hereby declare the following to be a full, clear, and exact description of the invention, such as will enable others 10 skilled in the art to which it appertains to make and use the same.

The invention relates to nursing bottles and has for its primary object to vent the same to insure a flow of the contents thereof from when the infant is nursing and to prevent waste of the food.

The invention furthermore precludes the collapsing of the nipple and the entrance of air into the stomach of the infant which is 20 productive of colic and other disorders resulting in discomfort both to the infant and nurse.

Other objects and advantages will be apparent and suggest themselves as the nature 25 of the invention is understood.

While the drawings illustrate an embodiment of the invention it is to be understood that in adapting the same to meet different conditions and requirements, various 30 changes in the form, proportion and minor details of construction may be resorted to without departing from the nature of the invention.

Referring to the accompanying drawings 35 forming a part of the application,

Figure 1 is a side view of a nursing bottle having a closing cap fitted to the vent opening,

Figure 2 is a view similar to Figure 1 of 40 a different form of bottle and nipple, having a vent cap fitted to the vent opening,

Figure 3 is an enlarged sectional detail of the portion of the bottle having the vent opening and the closing cap fitted thereto, 45 and

Figure 4 is a view similar to Figure 3, having the vent cap fitted to the vent opening.

Corresponding and like parts are referred 50 to in the following description and designated in the several views of the drawings by like reference characters.

The numeral 1 designates the body of the bottle which may be provided with a breast nipple 2 or a stalk nipple, said bottle being 55 provided with graduations and of any preferred form. A vent opening 4 is provided in a side of the bottle near the bottom thereof and a collar 5 projects outwardly from the bottle in line with the vent opening and is externally screw threaded. The vent opening 4 may be sealed by means of a closing flap 6, but when the bottle is in active 60 service for feeding the infant, the closing cap 6 is replaced by a vent cap 7 which is preferably of rubber and fitted to the collar 5, said vent cap having one or more vent openings 8 to admit air into the bottle as the contents are drawn therefrom. A retaining 65 ring 9 confines the vent cap 7 to the collar 5 so as to prevent displacement thereof. The form of bottle preferred has an approximately flat side for the bottle to rest upon and thereby hold the side provided with the vent opening 4 upward to prevent any possible waste of the food through the vent. 70

When the bottle is not in actual service, the vent opening is closed by means of the cap 6, but when in action for feeding the infant, the closing cap 6 is replaced by the 80 vent cap 7. As the contents are drawn from the bottle, air enters through the vent thereby preventing collapse of the nipple and insuring a positive supply of food to the infant, thereby obviating disorders resulting 85 from a collapsed and dry nipple.

What is claimed is:

A nursing bottle in addition to its usual flexible nipple engaging outlet having a collar relatively close to its closed end and provided with a vent opening therethrough, 90 said collar projecting exteriorly of the bottle, and a vent cap in the form of a flexible nipple applicable to said collar, either of said nipples being adapted to be used as an 95 outlet and the other nipple as a vent.

In testimony whereof I affix my signature in presence of two witnesses.

VENIE A. ISAAC.
